UNITED STATES PATENT OFFICE.

WILLIAM E. WINE AND WILLIAM F. CREMEAN, OF TOLEDO, OHIO.

CAR-DOOR-LOCKING DEVICE.

Application filed January 12, 1922. Serial No. 528,607.

To all whom it may concern:

Be it known that WILLIAM E. WINE and WILLIAM F. CREMEAN, citizens of the United States, residing at Toledo, in the county of Lucas and State of Ohio, have invented certain new and useful Improvements in Car-Door-Locking Devices, of which the following is a specification.

Our invention relates to new and useful improvements in car door locking devices and has among its objects to provide means for supporting the door in a temporary or partly closed position; to provide a fulcrum point whereby the door may be easily forced or pried from its temporary position to a locked position and means for preventing longitudinal movement of the free edge of the door in either a forward or rearward direction.

As is well known to those skilled in the art, drop bottom doors of freight cars soon become warped and distorted in service, due both to the rolling action of the car and to the heavy loads imposed upon the doors, and although the doors may be raised and nearly closed, relatively great force has to be applied at the final movement of the doors to force them to a closed position.

Also, the doors have a tendency to move longitudinally or shift which is damaging to the hinged connection and after relatively short service, the doors often have to be repaired.

The invention, shortly to be described in detail, provides locking means which will support the doors in a temporary position, from which position they will be pried to a closed position and there securely locked; a fulcrum means being provided for each door which also acts as a guide for the closing of the door and prevents the longitudinal movement of the door in one direction, while the main supporting member or pivotal hook locks the door in its uppermost and closed position and also prevents longitudinal movement of the door in the opposite direction.

With these and other objects in view our invention consists in certain new and novel structures, and combination of parts as will be hereinafter more fully described and pointed out in the claims.

Referring now to the drawings showing a preferred embodiment of our invention, Fig. 1 is a diagrammatic view showing

the locking means applied to each of the doors on one side of the car.

Fig. 2 is a view in elevation showing a fragmentary portion of the side of the car, the locking device being shown as holding the door in its closed position.

Fig. 3 is a sectional view taken on line 3—3 of Fig. 2 and looking in the direction of the arrow.

Fig. 4 is a fragmentary detailed view showing the door supported in a temporary and partly closed position, and

Fig. 5 is a fragmentary detailed sectional view taken on line 5—5 of Fig. 4.

Referring now to the several views showing a preferred embodiment, there is shown a freight car 1, having the upright supports 2, a portion of the transverse support 3, a channel section 4 (see Fig. 3), a portion of an upright sheathing 5 and the floor 6. A portion of the floor 7 is cut away and extending beneath this portion is the door 8 which is hinged at its inner end to a bracket 9, which in turn is riveted to an angle 10 and a portion of the center sill 11. 75

Further referring to Figs. 3 and 5, there is shown beyond the outer free edge of the door, a bracket 12 which is riveted to one leg of the channel 4 and to which bracket 12, are riveted the lower ends of the upright supports 2.

The door 8 is shown as made up of a plurality of wooden planks 13, over which may be placed a metal covering 14, and bolted to the bottom of the door and extending from its inner end to a distance beyond its outer end, is the angle 15.

Also bolted or riveted to the lower leg of the section 4 is the plate 16, which plate, as will be noticed in Figs. 2 and 4, is so positioned that it will form a stop and guide against which the vertical leg of the angle 15 will abut when the door is in its closed position. This plate 16 is provided with the opening 17 in which may be placed a rod 100 or bar 18 to pry the door to a closed position as will shortly be described, and is beveled at its lower edge.

Referring now to the supporting and locking means as attached to the body of the car, it will be seen that a housing 18 is applied to the outside of the car and may be riveted or otherwise secured to the section 4, which, in reality is a side sill.

This housing 18 has pivotally mounted 110

therein the hook 19, which hook is provided with the temporary supporting ledge 20 and the main supporting ledge 21. Also pivotally mounted in the housing 18 and to the rear of the hook 19 is the dog 22, which, when jammed against the hook 19 will hold the hook in its forward locked position, as clearly shown in Fig. 2.

It will be noticed that by the hook engaging the outer end of the angle 15 and, at one side thereof, and the plate 16 abutting against the other leg of the angle, the door is prevented from any lateral or transverse movement. Furthermore, the door will be tightly locked in its closed position and the dog will hold the hook firmly under the free edge of the angle 15 on the door.

The operation of the door and the locking device is exceedingly simple. Presuming that the dog 22 is swung rearwardly as shown in Fig. 4, the door will be first raised manually until the end of the angle 15 may be engaged by the temporary supporting ledge 20 of the hook 19. From this temporary supported position the door may be pried to its final and locked position by inserting the bar 18 within the opening 17 of the plate 16 so that the inner end of the bar 18 will engage the door. After the door has been pried or forced to its closed position, the hook 19 will be forced under the outer end of the angle 15 so that the ledge 20 of the hook will engage the said angle and support the door. When the door is thus in its supported position, the dog 22 will be jammed downwardly and the door tightly locked in its closed and supported position.

From the foregoing it will be seen that we have provided a locking device which will first support the door in a temporary position, and from which position the door may be readily pried or forced to a locked position, which is accomplished by providing a fulcrum point and temporary supporting means. Again by positioning the bracket 16 to abut against the one leg of the angle 15 and having a hook engaging the opposite leg of the angle, not only will the door be rigidly supported in its closed position, but will also be held tightly against transverse or lateral movement. The arrangement of the parts as shown in the drawings contemplates that the hook shall be forced under the angle 15 in finally closed and supported position to such an extent that further inward movement of the hook is arrested by contact of the angle against the side of the hook. When the hook is now locked, as by means of the dog 22, it will be seen the slippage of the door away from the plate 16 will be prevented by the jamming of the door angle against the side of the locked hook 19 as just described. And the plate 16 will in itself prevent slippage of the door in the opposite direction.

The locking device is one that may be readily applied to the different types of cars now in service.

Many slight changes may be made without in any way departing from the spirit and scope of the invention.

What we claim as new and desire to secure by Letters Patent is:—

1. In a door device for railway cars, a door hinged to the car body, a bracket affixed to the door, a guide affixed to the car body and arranged to cooperate with the said door bracket to prevent longitudinal movement of the free edge of the door in one direction with respect to the car body, and means for supporting the free edge of the door from the car body, said supporting means including means for preventing longitudinal movement of the free edge of the door in the opposite direction with respect to the car body.

2. In a door device for railway cars, a door hinged to the car body, a supporting bracket affixed to the door, a door-supporting member pivoted upon the body and arranged to be swung from one side of the said supporting bracket into a position cooperating therewith to support the door in closed position, a member affixed to the car body in such position as to guidably cooperate with the opposite side of the said supporting bracket, means associated with the said door-supporting member and the supporting bracket for limiting the movement of the former into engaging position, and means associated with the door-supporting member for holding the same in engagement with the door-supporting bracket.

3. In combination with a car having a drop door, a member secured to the bottom of the door, a pivotal hook secured to the side of the car body, and engaging the outer end of the member on said bottom of the door, means fastened to the car body and located to the other side of the member on the bottom of the door from that of the hook, said hook supporting said door, and locking the same in its closed position and said hook and said means that is secured to the side of the car body holding the door against transverse movement.

4. In combination with a car having a drop door, a member secured to the bottom of the door, means secured to the side of the car and abutting said member to prevent lateral movement of the door in one direction, a pivotal hook secured to the car body and on the opposite side of said member, said hook supporting the door in its closed position and preventing lateral movement of the door in the opposite direction, and an auxiliary means formed on said hook to hold the door in a partly open position.

5. In combination with a freight car having a drop bottom door, an angle secured

to the bottom of said door and extending beyond the free edge thereof to form a ledge, a plate secured to the side of the car body adjacent said ledge when the door is 5 in its closed position to thereby prevent lateral movement of the door in one direction, a hook pivotally mounted on the side of the car body above said ledge and engaging said ledge to support the door in a closed position 10 and prevent lateral movement of the door in the opposite direction, an auxiliary ledge formed on said hook to hold the door in a temporary position, and said plate arranged to provide a fulcrum for means for 15 prying the door from the temporary ledge to its final supported position on said hook.

6. In combination with a freight car having a drop bottom door, an angular member secured to the door and extending outwardly beyond the free edge thereof to form a supporting ledge, a plate secured to the car body and located adjacent one leg of said angle when the door is in its closed position, a hook pivotally mounted on the 20 side of the car above said ledge and said hook engaging the upper leg of said angle to thereby support the door and cooperate with said plate to prevent lateral movement of the free edge of said door, an auxiliary 25 supporting ledge formed on said hook for engaging said angular door member and holding the door in a partly opened position, said plate provided with an opening for the insertion of a bar to lift said door 30 to its final closed position, and means for holding the hook in its final forward and locked position.

7. In combination with a freight car having a drop bottom door, an angular member

secured to the door and extending outwardly beyond the free edge thereof to form a supporting ledge, a plate having its lower edge bevelled to form a guide, said plate secured to the car body and located adjacent one leg of said angle when the door is in its closed position, a hook pivotally mounted on the side of the car above said ledge and said hook engaging the upper leg of said angle to thereby support the door and cooperate with said plate to prevent lateral movement of the free edge of said door, an auxiliary supporting ledge formed on said hook for engaging said angular door member and holding the door in a partly opened position, said plate provided with an opening for the insertion of a bar to lift said door to its final closed position, and means for holding the hook in its final forward and locked position.

8. In a door device for railway cars, a door hinged to the car body, a bracket affixed to the door, a guide affixed to the car body and arranged to cooperate with said bracket to prevent longitudinal movement of a free edge of the door in one direction with respect to the car body, means for supporting the free edge of the door, and also cooperating with said bracket, said supporting means preventing longitudinal movement of the free edge of the door in the opposite direction with respect to the car body, and said guide providing a seat adapted for the reception of means for assisting in opening and closing the door.

In testimony whereof we affix our signatures.

WILLIAM E. WINE.

WILLIAM F. CREMEAN.
